UNITED STATES PATENT OFFICE.

WARREN B. HOWE, OF CHICAGO, ILLINOIS, AND FRANK B. DAVIDSON, OF BROOKLYN, NEW YORK, ASSIGNORS TO HOWE AND DAVIDSON COMPANY, OF EAST ORANGE, NEW JERSEY, A CORPORATION OF NEW JERSEY.

CARTON.

No. 825,539.

Specification of Letters Patent.

Patented July 10, 1906.

Application filed November 24, 1900. Serial No. 37,568.

To all whom it may concern:

Be it known that we, WARREN B. HOWE, of Chicago, in the county of Cook and State of Illinois, and FRANK B. DAVIDSON, of Brooklyn, in the county of Kings and State of New York, have invented certain new and useful Improvements in Cartons; and we do hereby declare that the following is a full, clear, and exact description thereof, reference being had to the accompanying drawings, and to the letters of reference marked thereon, which form a part of this specification.

This invention relates to improvements in paper boxes or cartons of that class in which the side walls thereof are provided with integral flaps which are interlocked to form the end of the box.

The invention is herein shown as embodied in a rectangular box which opens at one side thereof and wherein both ends of the box are formed by a plurality of interlocking flaps; but the invention may be applied to other shaped cartons and to cartons having but one end wall.

The invention consists in the matters hereinafter set forth, and more particularly pointed out in the appended claims.

In the drawings, Figure 1 is a perspective view of a rectangular carton made in accordance with our invention. Fig. 2 is a perspective view of one end of the carton with the side and bottom walls of the box set up, but with the interlocking flaps opened outwardly away from their locking positions to more clearly show the construction thereof. Fig. 3 is a similar view showing in their closed positions all the end flaps but that carrying the locking-tongue and the locking-tongue partially inserted into the locking-slit. Fig. 4 is an inside view of the end wall of the box with the several flaps in their interlocked positions. Fig. 5 is a view of one end of the blank from which the carton is made.

As shown in the drawings, the carton consists of a top wall a , two parallel side walls a' , a bottom wall a'' , and end walls a''' , the latter consisting of a plurality of interlocking flaps. Each of said end walls comprises three flaps—a flap a^4 , connected with one side wall of the box, a flap a^5 , connected with the other side wall thereof, and a flap a^6 , connected with

the bottom wall of the box. The blank for forming the carton (indicated by A in Fig. 5) consists of connected parts lettered a , a' , a'' , a^4 , a^5 , and a^6 , corresponding with the correspondingly-lettered parts of the box. One of said flaps, a^4 , is provided with a tongue and another, a^5 , with a slit, which is engaged by said tongue and by which the end walls are locked from lateral displacement. The remaining or third flap, a^6 , is provided with a narrowed extremity, which when the flaps are folded enters between the flaps a^4 and a^5 at one side of the center of the box end. The top wall a of the box in the particular construction shown is formed on one edge of the blank and is connected with one of the side walls, so that it may be disconnected at its free edge from the other side wall to open the box, as indicated in Figs. 2, 3, and 4. The free edge of said top wall, moreover, as shown, is provided with a longitudinal narrow flap C, which fits inside of the upper edge of the adjacent side wall of the box when the top wall is in its closed position. The upper edge of said side wall, which is engaged by the free edge of the top wall, is provided with a notch a^{18} , by which the finger may engage the said flap C of the top wall to facilitate opening the carton.

The flap a^6 is provided with a slit a^7 , which preferably extends from the side wall of the box at a point near the top of the box obliquely downward and terminates near the center of the box end. Said flap a^6 is preferably rectangular in form and of such width that when the blank is folded or is in its closed condition it engages at its upper and lower margins the top and bottom walls of the carton. The flap a^4 is provided with a locking-tongue a^8 , which is so shaped and located that its free end or extremity is directed downwardly when the flaps are folded inwardly and is adapted to enter said slit a^7 and form the locking connections between said flaps. The tongue-bearing flap a^4 is made of a width at its side which is attached to the side wall a' equal to the width of said side wall, and the tongue a^8 is located at or adjacent to the margin of said flap remote from said side wall. Said flap a^4 is notched at its lower edge or lowermost lateral margin to form said tongue, and the margin a^{11} of the

flap at the inner side of said notch is oblique and extends diagonally across the flap from one lower corner thereof to about the center of the flap. Preferably the inclination of 5 said margin a^{11} is such that a line forming an extension thereof will intersect the vertical side wall of the box at a point somewhat below the top margin of the side wall. When the parts are folded, as seen in Fig. 1, the 10 margins of the flaps appear as radial lines on the end of the box. Said flap a^4 is of such width that the outer margin of the tongue when the flap is in its closed position is located adjacent to the side wall a' , to which 15 the flap a^6 is attached, and extends substantially across the end of the carton. A flap B is preferably attached to the upper edge of the flap a^4 and is so arranged that when the carton is set up it extends within the carton 20 beneath the top wall thereof.

The tongue-bearing flap a^4 is provided at the point or angle where the inner margin a^{14} of the locking-tongue intersects the oblique margins a^{11} of the said flap with a notch a^{13} , 25 which extends in alignment with said oblique margin a^{11} . The inner end of said notch a^{13} is so located with respect to the adjacent end a^{12} of the locking-slit a^7 that when the flaps are interlocked and in their normal positions 30 or in position to hold the end of the box in its rectangular form the margins of the paper at the said inner end of the notch a^{13} and at the end a^{12} of the slit a^7 will be engaged or in contact with each other. The angular 35 position of the notch a^{13} is such, moreover, that when the tongue is inserted in the slit and parts are interlocked no disengagement of the interlocked flaps can be effected by strain coming on the two flaps outward in 40 the direction of their planes or in direction to pull them apart such as will be brought on the flaps by outward pressure on the side walls of the contents of the carton, but such strain will tend to more firmly interlock 45 the parts. Moreover, the distance from the corner a^{15} of the box to which said flap a^4 is attached to the inner end of the notch a^{13} , measured along the edge or margin a^{11} of the flap a^4 , is equal to the distance from 50 the said corner of the box to the inner end a^{12} of the slit a^7 when the flaps are folded together, while the distance from the same corner of the box to the inner end of the margin a^{14} of the tongue a^8 is less than the 55 distance from said corner to the said inner end a^{12} of said locking-slit, so that in the act of inserting the tongue a^8 into the slit a^7 the inner part of the margin a^{14} will come against the end a^{12} of the locking-slit and by its pressure thereon produce slight distortion of the 60 end of the box until the tongue is fully inserted and the notch a^{13} reaches and engages the end a^{12} of the slit, when the edge of the material at the end a^{12} of the slit will enter the 65 notch a^{13} and the parts will resume their

natural or normal positions. After the end of the locking-slit is thus interlocked with the notch a^{13} any strain on the two flaps in the direction to spread apart the sides of the box would merely result in the parts becoming more firmly interlocked, and the tongue cannot be drawn out of the slit by such pressure, because the inner end of the slit will in an effort to withdraw the tongue from the slit be brought against the side edge of the 70 said notch, which latter is arranged transverse to the tongue or practically at right angles to the direction in which the tongue must be moved in order to withdraw it from said slit. From this construction it follows 75 that after the parts have been interlocked, as described, they cannot be disconnected except by tearing off, breaking, or distorting the projecting part of the edge a^{14} of the tongue adjacent to the notch a^{13} . To facilitate the insertion of the tongue in the slit a^7 , the said inner edge a^{14} of the tongue is inwardly curved or made concave in form, as shown in the drawings, so that as the flap a^4 is swung or moved about the corner a^{15} of the 80 box as a center during the insertion of the tongue in the slit, as illustrated in Fig. 3, the said inner edge a^{14} of the tongue will slide along the end a^{12} of the slit until the inner 85 part of said edge a^{14} is reached, when by 90 reason of the outward inclination of the said inner end of said edge a^{14} the flap a^4 will be drawn inward through a slight bending, yielding, or distortion of the end of the box until the notch a^{13} reaches the slit, when the 95 parts will become engaged, as before described, and the end of the box will spring back to its normal or natural position.

As a further improvement in boxes with interlocking flaps of the general character described, the flap a^4 is so constructed to engage at one margin thereof with one of the side walls of the carton and at its other margin with the locking-tongue at the place where the latter enters the locking-slit. To 105 secure these results, the flap a^4 , as shown, is made equal in width to the bottom wall of the carton at its point of attachment thereto, and its outer end is narrowed by cutting away the flap at one side only, so as to form 110 an oblique part a^9 and a part a^{10} substantially parallel with the opposite edge of the flap, which latter is made perpendicular to the line at which the said flap a^4 joins the bottom of the box, so that the outer part of 115 said flap a^4 consists of a narrow part or tongue a^{11} , located at one side of the center line thereof and which when the flaps are folded together rests between the flaps a^4 and a^6 . The width of said tongue a^{11} is such that 120 when the flaps are folded together the side margin a^{10} of said tongue will engage the locking-tongue a^8 at the place where the latter enters the slit a^7 . The parts are 125 preferably so proportioned, moreover, that when 130

the flaps are folded the said edge a^{10} of the flap a^6 coincides with the inner end a^{12} of the slit a^7 and will enter the notch a^{13} , the result being that separation of the interlocked flaps 5 a^4 and a^6 is prevented by engagement of said notch a^{13} with the said edge a^{10} , as well as with the edge of the flap at the inner end of the slit a^7 .

By so constructing the flap a^6 that the 10 margin a^{10} will interlock with the notch a^{13} described and by also so constructing the opposite side edges of said flap a^6 that it will bear against the side edge a' of the box where the flap a^6 joins said side a' an additional means 15 is provided for holding the end of the carton rigidly in its rectangular form and preventing distortion thereof under inward pressure on opposite corners of the box.

In order to enable the tongue a^8 to be 20 easily inserted into and removed from the locking-slit a^7 , one or more slits a^{16} , arranged to extend laterally from said slit a^7 , are provided in the flap a^6 , said slit or slits a^{16} serving to make the edge of the paper above the 25 slit a^7 flexible, so that it will readily yield inward on pressure being applied thereto, and thereby permit the tongue of the flap a^6 to be easily and quickly inserted in the act of interlocking the parts. This result will be 30 well attained by the use of one slit a^{16} , and one only will be ordinarily used for small boxes; but as a preferable construction two slits are used, as shown in the drawings, said slits being laterally separated from each 35 other. Said two slits a^{16} a^{16} form a flexible tongue a^{17} , the free end of which is adapted to yield inwardly, and thereby permit the ready insertion of the tongue into the slit a^7 . The slit or slits a^{16} will be located at some 40 distance from said inner end a^{12} of said slit a^7 , so as not to interfere with the proper interlocking connection of the outer end of the slit with the notch a^{13} , as hereinbefore described.

45 We claim as our invention—

1. A paper box or carton having connected bottom and side walls, each of which is provided with a flap, the flap on one side wall being provided with a slit and the flap on the 50 other side wall with a tongue which extends laterally from the flap and is adapted to engage at its inner edge with the adjacent end of the slit in a manner to hold the sides of the box from spreading apart, and the flap on the 55 bottom wall being cut away at one side to form a narrow end located adjacent to the side wall to which the tongue-bearing flap is attached and adapted to enter between the interlocked flaps on the side walls.

60 2. A paper box or carton having connected bottom and side walls, each of which is provided with a flap, the flap on one of the side walls being provided with a slit and the flap on the other side wall with a tongue which 65 extends laterally from the flap and is adapted

to engage at its inner end the adjacent end of said slit in a manner to hold the sides of the box from spreading apart, and the flap on the bottom wall being adapted to enter between the interlocked flaps on the side walls 70 and to engage at one of its lateral edges the tongue-bearing flap in the angle at the junction of the tongue with the body of the flap.

3. A paper box or carton having connected bottom and side walls, each of which is provided with a flap, the flap on one of the side walls being provided with a slit and the flap on the other side wall with a tongue which extends laterally from the flap and is adapted to engage at its inner end with the 75 adjacent end of the slit in a manner to hold the sides of the box from spreading apart, and the flap on the bottom wall being adapted to be folded between the interlocking flaps and to engage at its lateral outer edge 80 the side wall to which the tongue-bearing flap is attached.

4. A paper box or carton having connected bottom and side walls, each of which is provided with a flap, the flap on one of the side 85 walls being provided with a slit and the other flap of the other side wall with a tongue which extends laterally from the flap and is adapted to engage at its inner edge with the adjacent end of the said slit in a manner to 90 hold the sides of the box from spreading apart, and the flap on the bottom wall being adapted to be folded between the interlocking flaps and constructed to engage at its outer lateral edge the side wall to which the 95 tongue-bearing flap is attached, and at its other lateral edge the tongue-bearing flap in the angle at the junction of the tongue with the body of the flap.

5. A paper box or carton having connected 100 bottom and side walls and provided on one of its side walls with a flap provided with a locking-slit which extends from its base toward its free end and on the other side wall with a 105 flap provided with an angular notch forming a laterally-extending locking-tongue adapted for insertion in the said slit with the end of the slit engaging the inner angle of said angular notch, and the bottom wall being provided with a flap which is narrower at its 110 outer end than the bottom wall to which it is attached, and having an oblique edge a^9 and an edge a^{10} which extend outwardly from said oblique edge and form the side margin of the narrower outer end of the flap. 115

6. A paper box or carton having connected 120 bottom and side walls, and having on its side walls flaps adapted to be folded together to form an end wall, one of said flaps being provided with a slit which extends from its base toward its free end and the other with a notch forming on one side of the flap a tongue adapted to enter said slit, the margin of the flap being provided at the base of the tongue with a secondary notch arranged trans- 125

versely to the inner margin of the tongue, said secondary notch being adapted to engage the outer end of said slit.

7. A paper box or carton having connected bottom and side walls, and having on the said side walls end flaps adapted to be folded together to form an end wall, one of said flaps being provided with a slit which extends from its base toward its free end, and the other with a notch forming on one side of the flap a tongue which is adapted to enter said slit, the margin of said flap at the base of the tongue being provided with a secondary notch which is arranged transversely to the inner edge of the tongue and which is adapted to engage the outer end of said slit when the tongue is inserted in the slit, said inner edge of its tongue at its part adjacent to the said secondary notch being so shaped as to draw toward each other the end flaps of the box by contact with the said outer end of the slit and thereby slightly distort the ends of the box during the insertion of the tongue in said slit.
- 25 8. A paper box or carton having connected bottom and side walls, and having on said side walls end flaps adapted to be folded together to form an end wall, one of said flaps being provided with a slit which extends from the base toward the free end thereof, and the other with a notch forming on one side of the flap a tongue which projects laterally from the flap on which it is formed and is adapted to enter said slit and having at the intersection of its margins which form said notch, a secondary notch arranged transversely of the inner margin of the tongue and which is adapted to engage the outer end of said slit when the tongue is inserted in the slit, said margin of its tongue in its part adjacent to the secondary notch be-

ing located at a less distance than the outer end of said margin from the corner of the box about which said tongue turns or swings in the act of inserting the tongue in the slit.

9. A paper box or carton having connected bottom and side walls and provided on its side walls with interlocking flaps and on its bottom wall with a flap which is interposed between the locking-flaps when the flaps are folded, one of said interlocking flaps being provided with a locking-slit which extends from its base toward its free end, the other interlocking flap being provided with an angular notch forming a laterally-extending locking-tongue for insertion in the slit with the end of the slit engaging the inner angle of said angular notch and said flap having a secondary notch located at the inner angle of said angular notch and transversely with respect to the inner edge of the tongue, and said interposed flap being made narrower at its outer end than the bottom wall to which it is attached, and having an edge a^{10} which coincides with the end of the locking-slit and enters said secondary notch when the flaps are folded.

In testimony that we claim the foregoing as our invention we affix our signatures, in presence of two witnesses, the said WARREN B. HOWE on the 8th day of November, A. D. 1900, and the said FRANK B. DAVIDSON on the 26th day of October, A. D. 1900.
